ELECTRIC COOKING OVEN

Ray C. Sandin, Northbrook, Ill., assignor to General
Electric Company, a corporation of New York

Application October 19, 1956, Serial No. 43,420

Term of patent 14 years

(Cl. D81—26)

Fig. 1 is a front perspective view of an electric cooking oven showing my new design;

Fig. 2 is a rear perspective view thereof.

I claim:

The ornamental design for an electric cooking oven, substantially as shown.
